UNITED STATES PATENT OFFICE.

CORNELIUS B. CORCORAN, OF PHOENIX, ARIZONA, ASSIGNOR TO UNDERWOOD TYPE-WRITER COMPANY, OF NEW YORK, N. Y., A CORPORATION OF DELAWARE.

TYPEWRITING MACHINE.

Application filed March 15, 1921. Serial No. 452,442.

To all whom it may concern:

Be it known that I, CORNELIUS B. CORCORAN, a citizen of the United States, residing in Phoenix, in the county of Maricopa and State of Arizona, have invented certain new and useful Improvements in Typewriting Machines, of which the following is a specification:

The present invention relates to typewriting machines and column indicators therefor.

Work-sheets adapted for tabulator and column work are usually provided with heads or captions at the upper ends of the columns. When a large number of items have been entered one below the other, the captions are so far removed from the printing line as to make it difficult for the operator to know whether the items are being entered in the correct column. The present invention provides means whereby the column captions may be kept prominently in view whenever desired, whether the typing is being performed at the beginning or at the end of a work-sheet. When not in use, said means may be swung to ineffective or inoperative position out of the way of the worksheets. The means employed comprises a strip similar to the portion of the work-sheet head containing the captions, which strip is held by a bail at the front of the platen in full view of the operator. The leading edge of the work-sheet passes under the strip to the rear of the machine. The strip may correspond to any type of work-sheet used and is readily replaceable. When it is no longer desired to use the machine for tabulator or column work, the bail may be swung to the rear of the platen to an ineffective position.

In certain classes of work, such as the typing of ledger-sheets, the sheets are filled out by a series of single-line entries, each made at a separate insertion of the work-sheet in the machine. The heading strip and the strip-holder of the present invention are especially adapted to facilitate and expedite work of this character. The strip is supported near enough to the line of writing and is sufficiently narrow to permit the operator to grasp the upper margin of the work-sheet above the strip and adjust the work-sheet both to register its columns with the divisions of the strip and to locate it in any

desired writing-line position at a single 55 operation.

It is a feature of the present invention that the heading strip is supported independently of the platen and out of contact therewith, so that a work-sheet may be adjusted freely between the strip and platen.

In accordance with one feature of the invention, the heading-strip support has an upwardly and rearwardly inclined rear face located to intercept the leading edge of the 65 work-sheet in the path which it naturally follows as it issues from the platen, to guide the sheet rearwardly behind the heading strip. With this construction, it is unnecessary to guide the sheet behind the heading 70 strip with the fingers, or to withdraw the heading strip during insertion of the sheet and later place it in effective position over the sheet.

Other features and advantages will hereinafter appear.

In the accompanying drawings,

Figure 1 is a front view of an Underwood standard typewriting machine with the invention applied thereto, only the necessary 80 co-operating elements of the machine being shown.

Figure 2 is a vertical section, taken on the line 2—2 of Figure 1.

Figure 3 is a detail view, in plan, of the 85 right-hand end of the strip-holder.

A platen 10 is fixed upon an axle 11, journaled in the end walls 12 of a platen-frame forming part of the usual typewriter carriage. Work-sheets 13 are adapted to 90 be fed around the platen by means of the usual feed-rolls 14. The platen may be rotated in either direction by knobs 15 fixed to the ends of the platen axle, or line-spaced by the line-space mechanism including the 95 line-space wheel 16.

The work-sheet illustrated is of the type adapted for use in bookkeeping or computing machines, and, in general, is typical of sheets adapted for use in tabulator or column work, in that it is provided with columns, each column having a caption at the head thereof, and the captions being in horizontal alignment. It will be seen as the sheet is line-spaced, the captions move further away from the printing line until the operator finds it difficult to distinguish the columns. If the sheet is long and of thin

material, the upper end will fall backwards, thus carrying the captions completely out of view of the operator. There is provided, at the front of the platen, a strip 20 preferably about a single line in width and comprising the line of column captions at the top of sheet 13. It is preferable to cut the strip directly from one of the sheets, in this way insuring a strip having exact duplicate captions.

The strip 20 is adapted to seat in a metal holder 21 having top and bottom inturned flanges 22 and 23. The holder is supported on the sides of the platen-frame by arms 24 and 25 pivoted on vertical brackets 26 and 27 fixed on the side walls 12. In Figure 2 arm 25 is shown pivoted on bracket 27 and 28. Each of the arms 24, 25 comprises a forwardly-extending portion 30, a laterally-disposed portion 31 bent horizontally at right angles to portion 30, and a downwardly-extending portion 32, at the lower end of which the holder 21 is attached.

Disposed between the portion 30 of each arm 24, 25 and each of the brackets 26, 27 is a thrust-link 35 composed of two telescoping parts 36 and 37, the former part being slidable in the latter part and having a compression spring 38 housed within part 37 and normally pressing the parts outwardly. Each thrust-link is pivoted at one end to the portion 30 of the arms 24, 25, and at the other end to the bracket 26 or 27 at point 39, above the pivots of said arms on the brackets. The springs 38 will tend to rotate arms 24 and 25 downwardly, until they strike the tops of the platen-frame side walls, thus limiting their downward movement. In this position, shown in full lines in Figure 2, the strip 20 is located at the front of the platen as shown in Figure 1, and slightly above the platen to allow the work-sheet to pass thereunder.

When it is no longer desired to tabulate, the holder and strip may be swung rearwardly about pivots 28 to the dotted-line position of Figure 2. The thrust-links hold the arms 24 and 25 in their rearward positions, since the springs press the telescoping parts outwardly, thus forcing the arms downwardly. The thrust-links are thus in the nature of two-way springs acting to either side of the vertical axes through pivots 28.

Referring to Figure 3, it will be seen that the arms and the thrust-links are positioned adjacent the inside surfaces of the brackets. The thrust-links lie between the arms and the brackets. The arms 24 and 25 are provided with hubs 40 to space them from said brackets a sufficient distance to allow free movement of the thrust-links. The thrust-links terminate at their ends in semi-cylindrical portions to permit the pivot screws to sink below the surface of the links, so

that their shoulders may operate against the flat portions of the semi-cylindrical surfaces.

The strip 20 is slidable laterally in the holder to enable the column captions thereof to be aligned with the columns of the work-sheet. A spring 45 fixed to arm 25 and pressing against the face of the holder is adapted to hold the strip in adjusted position.

A side edge gage 50, adjustably mounted on a paper-table 51, may be used to locate the work-sheets lengthwise of the platen, relatively to the strip 20 and relatively to tabulator-stops (not shown).

By reference to Figures 1 and 2, it will be understood that the holder 21 for the index-strip 20 is so positioned by engagement of the arms 24 and 25 with the ends of the platen-frame as to cause the index-strip to be located at the front of the platen between the printing line and a horizontal plane passing through the top of the platen, and substantially in the position, relatively to the printing line, normally occupied by the row of captions on the work-sheet when typing is begun on the sheet. In other words, the distance between the printing line on the platen and the row of captions on the strip 20 in the holder 21 is substantially equal to that by which the average operator spaces the first line of typing from the row of captions or heading of a work-sheet. In placing a work-sheet into the machine with the strip-holder 21 and strip 20 in operative positions, the vertical lines on the strip 20 at opposite sides of a caption are aligned with the lines on the work-sheet which bound the column having the same caption. A heading for a work-sheet in the form of a row of captions can best be observed by the operator of a typewriting machine when the captions are in position for having the first line written on the work-sheet. In the use of the present invention, the index-strip 20 enables the captions to be continued substantially in such position during the typing down a sheet from top to bottom, so that the captions are always in a position to form a heading for the portion of the work-sheet being written upon, so located as to best facilitate the filling in of the sheet. This provision for continuing the captions during typing down a work-sheet substantially in the positions, relative to the printing line, which they normally occupy on the work-sheet when work is first begun upon it, is a novel and important feature of my invention.

The strip-holder 21 and strip 20 are made relatively narrow, so as to cover but a small area on a work-sheet and to render the work-sheet readily visible both above and below the strip-holder, and the holder 21 is also so positioned as to locate the index-strip 20

closely adjacent to the platen 10 to facilitate comparison of the writing below the strip 20 and strip-holder 21 with the writing above them as well as with the captions on 5 the index-strip. For example, in writing figures in any of the columns on the work-sheet, the figures being written below the strip-holder 21 may be readily compared with those written above it, in order to assure the writing of units under units, tens 10 under tens, etc.

The downwardly-extending portions 32 of the arms 24 and 25 of the strip-holder 21 are so arranged as to cause the strip-holder 15 to be so inclined downwardly and forwardly toward the operator as to present the face of the index-strip 20 substantially at right angles to the line of sight of the operator in observing the strip. Such an 20 arrangement of the strip 20 best facilitates its inspection and use by the operator.

The guidance of a work-sheet around the platen of a typewriting machine to the printing line involves but small difficulty, 25 whereas the guidance of the strip rearwardly from the printing line necessitates the provision of members which offer more or less obstruction to the manipulation of the work-sheet in the use of the machine. It 30 will be understood by reference to Figure 2 that the under surfaces of the extensions 32 of the arms 24 and 25 and the under surface of the strip-holder 21 extend downwardly and forwardly across the vertical 35 plane tangential to the platen 10 at the printing line. This construction enables a work-sheet to be passed from the printing line between the strip-holder 21 and the platen 10 without the provision of guiding 40 means other than that for guiding the strip to the printing line, and also enables the strip-holder 21 and the downwardly-extending portions 32 of the arms 24 and 25 to serve as guiding means for properly directing 45 the strip in its movement away from the printing line rearwardly of the platen. The necessity for using other means for guiding the work-sheet rearwardly of the printing line is thereby obviated.

50 The portions 30 of the arms 24 and 25 of the strip-holder 21 are of such a length that, when they are swung rearwardly on the platen-frame, they carry the strip-holder 21 and strip 20 to ineffective position 55 down behind the upper end of the paper-table 51. In such positions of the strip-holder 21 and strip 20, they are entirely out of the way of the work-sheet, so that a work-sheet, in the typing of which it is not 60 desired to use the strip 20, may be typed as conveniently on a machine provided with the strip 20 and strip-holder 21 as on a machine which is not provided with such parts.

65 Variations may be resorted to within the

scope of the invention, and portions of the improvements be used without others.

Having thus described my invention, I claim:

1. In a front-strike typewriting machine for typing on a work-sheet which includes a series of headed columns, a platen, a platen-frame, a paper-guiding shelf at the introductory side of the platen for guiding work-sheets to the platen, feed-rolls co-operating with the platen for feeding the work-sheet, means for casting off the feed-rolls to permit adjustment of the work-sheet, a narrow column locating and indicating heading strip having characteristic column headings and divisions identical with column headings and divisions on the work-sheet, a U-shaped heading-strip carrier having rearwardly-extending legs beyond the end of the platen which are pivotally mounted at their rear on the platen-frame and are arranged normally to co-act with the end portions of the platen-frame to support the heading strip close to the platen but independently of the platen and out of contact therewith and immediately above the line of writing in full view of an operator seated at the machine in writing position, the construction and arrangement being such that the feed-rolls may be cast off and a work-sheet adjusted freely between the heading-strip carrier in its normal position and the platen to register the work-sheet columns with the corresponding heading-strip divisions, and the heading strip and its carrier being sufficiently narrow and located sufficiently near the line of writing to permit the operator to grip the leading margin of the work-sheet above the heading strip and adjust the sheet to any writing-line position at the same operation and simultaneously with the registering of its columns with the divisions of the heading strip, and the heading-strip carrier being swingable on its pivot to a position to locate the heading strip and carrier completely out of the way in an ineffective position behind the paper-guiding shelf at the introductory side of the platen when it is desired to convert the machine for work which does not require the use of the heading strip, and means for retaining the carrier in effective or ineffective position.
2. In a front-strike typewriting machine for typing on a work-sheet which includes a series of headed columns, a platen, feed-rolls co-operating therewith, paper-guiding means for guiding a work-sheet around the platen and vertically upward past the line of writing, a platen-frame, a work-sheet deflector mounted on the platen-frame and having an upwardly and rearwardly inclined surface a short distance above the line of writing and intersecting the vertical plane of the line of writing to intercept the leading

edge of a work-sheet guided vertically past the printing point and deflect it to the rear as it is inserted to writing position, said deflector being supported close to the platen 5 but independently thereof and out of contact therewith, and a column locating and indicating heading strip having characteristic column headings and divisions identical with column headings and divisions on the 10 work-sheet carried by the deflector immediately above the line of writing and in full view of the operator, the construction and arrangement being such that the feed-rolls may be cast off and the work-sheet ad- 15 justed freely between the platen and the de-

flector to register the work-sheet columns with the corresponding divisions of the heading strip, and the heading strip and deflector being sufficiently narrow and located sufficiently near the line of writing to permit the 20 operator to grip the leading margin of the work-sheet above the heading strip and to adjust the sheet to any writing-line position at the same operation and simultaneously 25 with the registering of its columns with the divisions of the heading strip.
